FLUE CLEANING IMPLEMENT WITH BLADE
FLEXIBLY CONNECTED TO SHAFT

Joseph E. Bower, Milwaukee, Wis.

Application June 6, 1946, Serial No. 674,893

6 Claims. (Cl. 15—242)

1

This invention relates to improvements in cleaning implements, and more particularly to hoe-like implements for cleaning soot and ashes out of the flues of furnaces.

An object of the invention is to provide a simple inexpensive cleaning implement for pipes, flues and the like, having a blade insertable in one position substantially parallel to the pipe surface and withdrawable in a position transverse to the pipe axis.

A further object is to provide such an implement in which the blade is controllable solely by manipulation of the simple rigid shaft.

Another object is to provide an improved coupling between an element and a spring.

The present invention results in an implement far more effective and easily manipulated than previously known devices of its kind and at the same time simple, inexpensive and durable in construction.

The above and still further objects and advantages may be carried into practical effect as described hereinbelow, with reference to the accompanying drawings in which:

Fig. 1 is a schematic view of a typical furnace flue showing an implement according to the present invention in operative position;

Fig. 2 is a fragmentary longitudinal sectional view of the blade end of an implement according to the present invention;

Fig. 3 shows the structure of Fig. 2 with the blade flexed into position for insertion in a flue;

Fig. 4 shows a modified blade form;

Fig. 5 shows a cross section of a pipe and end views of the cleaning implement in position for insertion (a) and in operative position in the pipe (b) as shown in solid and chain lines, respectively.

Like reference characters indicate similar parts throughout the several figures of the drawings.

In the embodiment of the invention shown in the drawing, a substantially rigid manipulating shaft 1 is provided at one end with a handle 2 of suitable known type. The shaft 1 may be suitably curved for most effective use in curved ducts and flues of the type shown in Fig. 1.

A short coil spring 3 is rigidly secured at one end to the extreme end of shaft 1, forming a universally flexible resilient coupling element. The end of the shaft 1 is preferably taper threaded for this purpose, or if desirable, the spring 3 may be spot welded or otherwise securely attached by known methods.

A rigid flat blade 4, preferably a disk-like plate of any suitable, durable material, is secured by

2

suitable means, such as screw 6, to the free end of the flexible tip 3 of shaft 1, a few turns of spring 3 being left free between the blade and shaft fastenings.

5 A collar 7 which may be attached to disk 4 as by welding, or formed integrally therewith, has an internal diameter equal to, or smaller than, the outside diameter of the spring or tip 3, and is provided to restrict expansion of the spring when screw 6 is inserted, making a solid connection. Preferably the collar 7 is provided with a small internal flange 7' which is engaged between the end of spring 3 and the disk 4, the collar 7, when so formed, is separable from disk 10 4 and is clamped in place by screw 6 and spring 15 3 in assembly.

As shown in Fig. 4, the blade 4 may be a simple stamped disk of sheet metal peripherally flanged as at 8 for strength and for other reasons 20 more fully set forth hereinbelow.

It will be readily apparent that other known forms of functionally equivalent flexible resilient coupling elements may be substituted for the coil spring 3 shown in the drawing.

25 The advantages of the present invention will be clearly apparent from the following description of its operation:

The implement of the invention is illustrated, in Figs. 1 and 5 (a and b) of the drawing, in typical positions employed for cleaning a curved furnace flue. Straight ducts may also be cleaned with implements embodying the invention, such implements may have less curved (or straight) shafts if to be used for very long straight ducts.

30 35 The implement is inserted in the cleanout opening 9 of a furnace flue 10 by pressing the disk-like blade laterally against the top, or side, of the inner surface of the flue and thrusting same into the flue while maintaining lateral pressure on shaft 1. The pressure on one edge of the blade 4 causes the coupling member 3 to flex through an angle of about 90° about a short radius which should be less than the radius of disk 4 as shown in Fig. 3. The disk 4 will readily

40 45 assume a position substantially parallel to the flue wall and shaft end, and may be easily slid along the flue without substantially disturbing the accumulation of ashes and soot in the flue. The blade is shown being inserted at a in Fig. 5.

50 When the disk 4 has been inserted as far as possible in the flue the operator ceases to maintain lateral pressure on the shaft 1, and resilient coupling 3 will cause disk 4 to assume its normal position substantially at right angles to the shaft end, and transverse to the flue axis.

The implement is then withdrawn, the blade 4 resting on the flue bottom and drawing the accumulated ashes and soot out of the cleanout opening. The implement is shown at b in Fig. 5, in position for withdrawal in operative relation to the flue.

It will be apparent that the universal flexibility of the blade 4 with relation to the shaft end is a distinct advantage in insertion of the implement, for a blade nearly as large as the flue opening can be readily inserted without pushing ashes away from the cleanout. Moreover, in inserting an implement into a curved flue it is often necessary to rotate the shaft somewhat, an operation which is facilitated in the present device by the universal flexibility of the blade.

Use of a blade formed as shown in Fig. 4 is advantageous not only because low in cost, but for the reason that, in operation, the flanged disk will act as a scoop and will be a more efficient ash and soot remover than a flat disk. Furthermore, the rounded turn of the flange will slide easily along the wall of the flue during insertion of the implement.

It will be understood that the specific embodiment described and illustrated is illustrative only, and that the invention includes such modifications and equivalents as may readily occur to persons skilled in the art, within the scope of the appended claims.

It is claimed and desired to secure by Letters Patent:

1. In a flue-cleaning hoe: a substantially rigid manipulating shaft; a universally flexible resilient coupling at one end thereof and extending therebeyond; and a substantially rigid flat disk element secured to said coupling, said blade being normally carried at right angles to said end of said shaft, and said coupling being universally flexible throughout a length not greater than the radius of said disk to permit said disk to assume a position parallel to said shaft end.

2. In a flue hoe: an elongated, curved, substantially rigid, manipulating shaft; a coil spring secured to one end of said shaft and projecting a few turns beyond the shaft end; and a disk-like blade element secured to the projecting end of said spring.

3. A flue hoe comprising, a substantially rigid shaft, a flexible resilient helical coil spring element secured at one end to one end of said shaft in coaxial shaft surrounding relation and projecting a few turns beyond said end of said shaft, a substantially rigid disk-like blade element, and means securing said blade element to the extending end of said spring element at substantially right angles to the longitudinal axis of said spring element and at a distance from said one end of

5 said shaft not greater than the radius of said disk-like blade element.

4. A flue cleaning implement comprising, a substantially rigid curved shaft, a flexible resilient coil spring coupling element rigidly secured at one end to and projecting a few turns beyond one end of said shaft, a substantially rigid blade element, and a relatively rigid fastening connecting said blade element with the extending end of said coupling element at substantially right angles to the longitudinal axis of said coupling element.

5. In a flue hoe: an elongated, substantially rigid manipulating shaft; a normally straight universally flexible resilient tip rigidly secured at one end to one end of said shaft and projecting a short distance beyond said shaft end and a rigid disk-like blade element secured to the projecting end of said universally flexible resilient tip at a distance from said end of said shaft not greater than the radius of said disk.

6. A flue hoe comprising: an elongated substantially rigid manipulating shaft; a universally flexible resilient spring element rigidly secured at one end to one end of said shaft and projecting a short distance from said end of said shaft; a substantially rigid disk-like blade element; and means rigidly securing said blade element to the extending end of said spring element at substantially right angles to the longitudinal axis of said spring element and at a distance from said one end of said shaft not greater than the radius of said disk the said spring element being of such form, dimensions and material characteristics as to be manually flexible between said shaft end and said blade element, through an arc of at least ninety degrees, without permanent set.
